UNITED STATES PATENT OFFICE.

ZOHER DOYLE, OF SPRING CREEK, MISSOURI.

DESIGN FOR A WASHING-MACHINE FRAME.

SPECIFICATION forming part of Design No. 26,366, dated December 1, 1896.

Application filed October 28, 1896. Serial No. 610,371. Term of patent 14 years.

To all whom it may concern:

Be it known that I, ZOHER DOYLE, a citizen of the United States, residing at Spring Creek, in the county of Phelps and State of Missouri, 5 have invented a new and original Design for Washing-Machine Frames or Stands, of which the following is a specification.

This invention relates to a new and original design for a washing-machine frame or 10 stand; and it has for its object to provide a design of this character that shall be both useful and ornamental.

The leading feature of the design resides in a frame or stand having oppositely-located 15 pairs of squared uprights, the squared uprights of one pair being closer together and of a greater length than those of the other pair, said squared uprights of both pairs being formed near their upper ends with cubical 20 enlargements having ornamental front faces, and the shorter of said uprights being formed at their upper extremities with straight cylindrical extensions, a pair of duplicate flat cross-pieces connecting the said cylindrical 25 extensions and having rounded ends, a rectangular crown-piece connecting the upper extremities of the long uprights and having a vertically-disposed crest projection provided with an ornamentally-scalloped edge 30 and an ornamental front face, a cylindrical cross-bar disposed between the cubical enlargements of the long uprights and having 35 annularly-enlarged end portions next to the cubical enlargements, and a plurality or group of spaced platform-strips disposed in the space between the opposite pairs of uprights and converging into the space between the long uprights.

In the accompanying drawing the figure is 40 a perspective view of a washing-machine frame or stand embodying the herein-described design.

Referring particularly to the drawing, 1 and 2 2 designate, respectively, oppositely-located pairs of squared uprights, the uprights 45 2 being closer together and longer than the uprights 1 of the opposite pair, and all of said uprights are formed near their upper ends with cubical enlargements 3, having ornamental front faces 4. The shorter uprights 1 50 are provided at their upper ends with straight cylindrical extensions 5, connected by a pair of duplicate flat cross-pieces 6, having rounded ends 7, and the upper ends of the longer uprights 2 are connected by a rectangular 55 crown-piece 8, having the vertically-disposed crest projection provided with an ornamentally-scalloped edge and an ornamental front face. A cylindrical cross-bar 10 is disposed between the cubical enlargements 3 of the 60 uprights 2 and is provided with enlarged annular end portions 11 next to the said cubical enlargements.

A plurality or group of spaced platform-strips 12 are arranged in a horizontal plane 65 in the space between the opposite pairs of uprights and converge at one end into the space between the long uprights 2. At the closely-arranged ends of the strips 12 is arranged between the uprights 2 a cylindrical vertical 70 post 13, having a reduced upper end portion 14.

What I claim is—

The design for a washing-machine frame or stand herein shown and described.

In testimony that I claim the foregoing as my own I have hereto affixed my signature in the presence of two witnesses.

ZOHER DOYLE.
